UNITED STATES PATENT OFFICE.

WILLIAM H. EPPERSON, OF SACRAMENTO, CALIFORNIA.

COMPRESSOR APPARATUS.

Application filed May 2, 1921. Serial No. 466,062.

To all whom it may concern:

Be it known that I, WILLIAM H. EPPERSON, a citizen of the United States, and a resident of Sacramento, county of Sacramento, and State of California, have invented a new and useful Compressor Apparatus, of which the following is a specification.

My invention relates to single acting compressors of the piston type and particularly to means for packing the piston rod in the cylinder.

An object of the invention is the provision of means for hermetically sealing the piston rod end of the cylinder without interfering in any way with the free movement of the piston rod nor passing the piston rod thru the usual type of packing boxes which are only relatively tight. Another object of the invention is the provision of an improved compressor particularly suitable for use in refrigerating apparatus. In apparatus of this character, one of the most important problems is to prevent the leakage of the refrigerant. In most of these devices the compressor shaft passes thru a stuffing box and it has been found impossible to prevent escape of more or less of the refrigerant material past the shaft. In other machines the stuffing box construction is avoided and splendid results are secured, but by means of very costly construction which makes the device prohibitive in price. It is therefore the broad object of my present invention to provide a compressor which can be manufactured at low cost and which provides no possible escape for the refrigerant, the circuit thru which the refrigerant material passes being completely sealed.

My invention possesses other objects and features of advantage, some of which with the foregoing, will be set forth in the following description of my invention. It is to be understood that I do not limit myself to the showing made by the said description, as I may adopt variant forms of my invention within the scope of the claims.

In the drawings, Fig. 1 is a vertical sectional view of my compressor apparatus. Fig. 2 is a vertical sectional view of a portion of a small refrigerator, in which my compressor finds one of its chief applications.

My compressor comprises a cylinder 2

having a flaring lower edge 3 and mounted in a vertical position upon the bed plate 4, conveniently set in the bottom portion of the refrigerator 6, which is of known type, and which therefore needs no detailed description. A single acting piston 7 is slidably arranged in the cylinder and is provided with a check valve 8 in the cross wall thereof to permit the passage of gases from the chamber below the piston to the chamber above the piston on its downward stroke.

The upper end of the cylinder is closed by the head 9 into which is connected, thru a check valve, the pipe 11, which joins the compression chamber of the cylinder to the condensing coils 12, emptying into the receiver 13. The receiver is connected by pipe 14, including the expansion valve 16, to the expansion coil 17, the end of which is connected by pipe 18 into the chamber below the piston. The inlet passage provided by the pipe 18 opens into the cylinder immediately below the piston in its lower position, and preferably, at the point where the lower edge of the cylinder begins to flare outwardly.

The piston rod for moving the piston is preferably formed in two parts, the inner part 21 pivotally connected to the piston in the usual way at its upper end and terminating at its lower end in a flange or head 22. The other half of the piston rod is of similar construction, being provided with a head 24 adapted to be bolted to the head 22 with the rods in alinement and terminating at its other end in a suitably formed eye for connection with the lever 26 mounted with the driving gear 27 and motor 28 upon the bed plate. Interposed between the two heads 22 and 24 is a flexible sheet or diaphragm 29 of leather, rubber, or other suitable material. The bolts 31 which secure the heads 22 and 24 together, of course pass thru the diaphragm, but the compression of the heads upon the material of the diaphragm is sufficient to form a tight closure about the bolts. The outer edge of the diaphragm seat is secured tightly to the flared end of the cylinder by means of a clamp ring 32, held by bolts to the flange of the cylinder. Here also the diaphragm acts as its own gasket to form a tight joint with the flange. The diaphragm is thus fixed at a point within its edge to the piston rod intermediate the ends thereof, and the edge

of the diaphragm is fixed to the cylinder. The diaphragm is applied and drawn tightly when the piston rod is at one end of its travel as shown in Fig. 2.

5 It will be seen from the above that the piston rod is permitted free movement while at the same time the end of the cylinder is hermetically sealed.

If leather or other porous material is 10 used for the diaphragm I deposit on the inside thereof, a thin layer 33 of Chinese clay or comparable material, and glycerin. Over this I then fill in a layer of glycerin 34. The clay is for the purpose of filling the pores 15 of the diaphragm to render it impervious and the glycerin which is inert in the presence of the refrigerant usually used, prevents the refrigerant from attacking the diaphragm. It is of course understood that any 20 other suitable materials may be substituted for either the clay or the glycerin.

In case I use rubber, or leather which has been treated to render it impervious, for the diaphragm I will not use the clay coating but in this case I will use the protective 25 layer of liquid which is inert in the presence of the refrigerant.

From the above it will be clear that in

operation the piston is reciprocated by the piston rod in a manner not at all different 30 from the usual construction of piston and piston rod, and the diaphragm will follow the piston back and forth not interfering with its movement but hermetically sealing the lower portion of the cylinder. 35

I claim:

1. The combination with a cylinder and piston therein, of a piston rod formed in two pieces adapted to be secured together, a leather diaphragm interposed between the 40 two pieces, means for securing the edge of the diaphragm to the cylinder, a layer of clay on the diaphragm and a layer of glycerin on the clay.

2. A compressor comprising a cylinder, a 45 piston in said cylinder, a rod for moving said piston, means for actuating said piston rod, a flexible diaphragm fixed to the piston rod and fixed at its edge to the cylinder, a layer of sealing material on said diaphragm, and a layer of protective liquid on 50 said sealing material.

In testimony whereof, I have hereunto set my hand.

WILLIAM H. EPPERSON.
